POURING BOTTLE STOPPER

John J. Daly, New York, N. Y.

Application August 8, 1936, Serial No. 94,910

10 Claims. (Cl. 40—4)

The present invention relates to an improvement in vented pouring spout devices for use on liquid holding devices such as beverage bottles and the like, and is used for dispensing such beverage from the bottles and to carry thereon advertising display matter.

The present device is intended to supply the foregoing noted functions and to provide a pouring stopper the component parts of which are rigidly assembled together and which will withstand the rigorous action of forcing the cork into and out of bottles during its use, without relatively bending the parts or separating them.

The foregoing and other features of advantage will be apprehended as the herein description proceeds, and it will be obvious that modifications may be made herein, without departing from the spirit hereof or the scope of the appended claims.

20 In the drawing,

Fig. 1 is an elevational view of the present device, with parts broken away;

Fig. 1a is a side view of the advertising panel removed from the assembly of Fig. 1;

25 Fig. 2 is a sectional view taken on the line 2—2, Fig. 1, looking in the direction of the arrows;

Fig. 3 is a sectional view taken on the line 3—3, Fig. 1, looking in the direction of the arrows, and

30 Fig. 4 is a sectional view, taken on the line 4—4, Fig. 1, looking in the direction of the arrows.

The present device, as in Fig. 1, comprises an advertising wing 1, which wing, Figs. 1a, 2 and 3, is a flat, semi-ovoid disc, having one portion of its edge at a and b, Fig. 1a, partaking of the curve of the pouring tube 2, Fig. 1, said edge a—b being interrupted by an outstanding bendable securing lug 10.

40 The lower portion of the wing, as viewed in Fig. 1a, also has a downstanding, anchoring lug 8.

The pouring tube 2, Fig. 1, has an upper curved portion, the lower end, as it enters the metallic domelike cap 5, and the cork extension 6 thereof, being substantially straight.

The tube 2, open at its upper and lower ends, is capped by a gravity swivel cap 3, and at the exposed curved portion is slotted to permit the seated introduction therein of the curved frontal edge a—b of the disc 1, thus to form a partition 9, within the tube 2, as shown in Figs. 1 and 3. The locking lug 10, protrudes through a lug slot provided in the incurved section 16 of the tube 2, said lug being then bent against said

section 16, as shown in Figs. 1 and 2, thus to lock the wing 1, in operative relation to the tube 2. The intrusion of the wing 1, into the pouring tube passage as illustrated in Figs. 1 to 3 inclusive does not interfere with the pouring of liquid therethrough, nor does the pouring tube leak, during the pouring operation.

The vent tube 4, Fig. 1, which is also located in the domelike cork cap 5 and the cork 6, as is customary, extends downwardly a distance 10 below the cork 6. The pouring tube 2 and the vent tube 4, where they pass through the cap 5 may be all soldered together, to insure rigid unit assembly. The cork 6 is firmly fitted by bores, around said tubes 2 and 4 and into the domelike 15 cap 5 a short distance, as indicated in Fig. 1, at the broken away portion.

The wing, Fig. 1, as assembled to the structure there shown, is also further anchored to the said assembly, by the introduction of its anchor lug 20 8 into the upper open end of the vent tube 4, as indicated in Figs. 1 and 4. As thus constructed, the torsion applied to the wing and tube assembly when applying the cork to a bottle does not injure the assembly or loosen it, as the assembled 25 structure is perfectly rigid, with a minimum of soldering.

I claim as my invention:

1. A pouring stopper for bottles comprising a cork, a cap therefor, a pouring tube in said cork, 30 a vent tube in said cork located adjacent said pouring tube, said latter tube having a longitudinal slit therein and an extending wing member mounted in said slit and vent tube.

2. A pouring stopper for bottles as set forth in 35 claim 1, in which the slotted pouring tube is provided with an aperture opposite said slit, said wing having a lug thereon which is entered into said aperture and bent over to lock said wing in said pouring tube and slit, and a prong on said 40 wing which is entered into the bore of the vent tube.

3. A pouring stopper for bottles, as set forth in 45 claim 1, in which the upper pouring end of the pouring tube is curved and the extending wing member mounted in the tube has its tube engaging edge curved to fit the curve of the pouring tube.

4. A pouring stopper for bottles comprising a 50 cork, a cap therefor, a curved pouring spout in said cork and cap, a vent tube in said cork and cap, and including an advertising wing comprising a disc having an edge conforming to the curve 55 of said spout, an extending bendable lug on said

edge and an adjacent edge having an extending anchoring lug thereon.

5. A pouring device and display means for a bottle stopper comprising a tube including an outer curved discharge section having extending longitudinally through the wall thereof on its convex side a slot, said section having in the concave side of its wall and opposite the first slot a short slot; a display disc including a wing portion, a concave base portion passing through the first mentioned slot and being disposed in the bore of the tube, said latter portion having its concave edge engaged against the convex face of said concave side, and an attaching lug extending from said base portion and engaged in the short slot, said wing portion and the tube section forming manipulating means for the stopper.

6. In combination with a bottle stopper comprising a cork, a pouring tube passing through the cork and including an outer discharge curved section having in its wall a long slot and a short opposite slot; a venting tube also passing through the cork and having an outer terminal at one end 25 of the long slot; a display disc including a wing extension and having a curved base portion disposed in the bore of the tube, said latter portion being passed through said long slot, there being a portion of said extension resting against said 30 terminal, and means integral with said base portion and being fixedly disposed in the short slot.

7. In combination with a bottle stopper comprising a cork, a pouring tube passing through the cork and including an outer curved discharge 35 section having in its wall on one side of the axis of the tube a long slot, said section having in its wall opposite the first slot a short slot; a venting tube also passing through the cork and having an outer terminal at one end of the long slot, 40 said end being adjacent the cork; a display disc including a wing extension and having a curved base portion disposed in the bore of said section, said latter portion being passed through the long slot; an attaching lug extending from said base 45 portion and being fixedly disposed in the short slot, and another lug extending from the wing

extension and being grippingly disposed in the bore of said terminal, said latter lug being of angular cross section.

8. A bottle stopper having therein a pouring tube including an outer curved discharge section 5 and a venting tube having an outer terminal adjoining said section, the wall of said section having in one side thereof an elongate slot and there being in said wall opposite the first slot a short slot; a flat display wing having its base passed through the long slot in closing relation therewith, said base being disposed in the bore of said section, there being passages on opposite sides of the base; an attaching lug extending from said base and forming a closure for the short slot, 10 and another attaching lug extending from the wing adjacent its base and being disposed in the bore of said terminal, said latter lug also providing 15 passages on opposite sides thereof.

9. The combination with a bottle stopper having therein a venting tube and a pouring tube having an outer discharge section curved to one side of the stopper, said venting tube including an outer terminal; of a display wing 20 extending to the opposite side of the stopper 25 and having a base portion so disposed in the bore of said section as to allow discharge of the contents of a bottle, said section having in the wall thereof a slot through which said base passes; and means integral with the wing extension 30 and fixedly disposed in the bore of said terminal, said means being also positioned so as to allow of air ingress to the bottle.

10. The combination with a bottle stopper having therein a venting tube and a pouring tube 35 including an outer section, said section being curved to one side and having in its convex wall a slot, said venting tube having an outer terminal; of a display wing extending to the opposite side and having a base portion disposed in the 40 slot so as to close the latter, and means integral with said wing and fixedly disposed in the bore of said terminal, said means being so positioned in the bore as to allow of air movement there-through.

JOHN J. DALY.
